191,514

TILE OR SIMILAR ARTICLE

Philip M. Brody, Scarsdale, and Frederic H. Rahr, New York, N.Y., assignors to Wood Conversion Company, St. Paul, Minn., a corporation of Delaware

Filed June 9, 1961, Ser. No. 65,529

Term of patent 14 years

(Cl. D18—2)

Fig. 1

FIG. 1 is a face view of a tile showing my new design.
FIG. 2 is an end view of the tile showing the bottom edge of FIG. 1.

In FIG. 1, the edges of the printed squares have contrasting tones against a lighter background.

We claim:

The ornamental design for a tile or similar article, substantially as shown and described.
